F. THORNTON, JR., AND F. F. FORSHEE,
DETACHABLE CIRCULATING WATER HEATER UNIT.
APPLICATION FILED JULY 19, 1920.

1,438,621.

Patented Dec. 12, 1922.

UNITED STATES PATENT OFFICE.

FRANK THORNTON, JR., OF MANSFIELD, OHIO, AND FRANK F. FORSHEE, OF FLINT, MICHIGAN, ASSIGNEES TO WESTINGHOUSE ELECTRIC PRODUCTS COMPANY, A CORPORATION OF MICHIGAN.

DETACHABLE CIRCULATING-WATER-HEATER UNIT.

Application filed July 19, 1920. Serial No. 397,421.

To all whom it may concern:

Be it known that we, FRANK THORNTON, Jr., a citizen of the United States, and a resident of Mansfield, in the county of Rich-
5 land and State of Ohio, and FRANK F. FORSHEE, a citizen of the United States, and a resident of Flint, in the county of Genesee and State of Michigan, have invented a new and useful Improvement in Detachable Cir-
10 culating-Water-Heater Units, of which the following is a specification.

Our invention relates to electrically-heated apparatus and particularly to electrical water heaters.

15 It has for one of its objects to provide a simple and relatively inexpensive form of water heater which may be easily and quickly assembled and disassembled.

Another object of our invention is to provide 20 a unitary type of heating element which may be assembled in any desired number of units and which shall employ novel means for electrically connecting the different units to each other and to the contact terminals.

In practicing our invention, we provide a plurality of substantially semi-tubular refractory resistor-supporting members, each member having a plurality of open longitudinally-extending resistor-supporting 30 grooves in the inner face thereof and a resistor wire located therein. We provide a ventilated terminal box located beneath the heating element and means for electrically connecting the heating elements together and to the terminals in the terminal box, said connecting means serving also to hold the several semi-tubular refractory supporting members in proper operative position relative to each other.

40 Referring to the single sheet of drawings,

Figure 1 is a view, partly in side elevation and partly in vertical section, of a device embodying our invention;

45 Fig. 2 is a cross-sectional view, along the line II—II of Fig. 1, of the device with the heat-insulating material removed;

Fig. 3 is a top plan view of the refractory resistor-supporting member;

50 Fig. 4 is a side view of the member shown in Fig. 3, and

Fig. 5 is a side view of the device embodying our invention as assembled and mounted

in connection with the ordinary type of hot-water tank.

55 A tubular member 1 has mounted at each end thereof a T-type connection 2. The outer open end of each of the members 2 may be closed by a plug 3 as shown. A lateral opening is provided in the member 2 into which the short length of pipe 4 (see Fig. 5) may be screwed to permit of a water connection being made with an ordinary hot-water tank 5. While the use of the members 2 and the plugs 3 is not essential 60 to the operation of the device, it is highly desirable, as their use permits the easy removal of any mineral matter which may be deposited in the tubular member 1 during the operation of the heater.

70 A substantially semi-tubular refractory resistor-supporting member 6 is provided with a plurality of longitudinally-extending resistor-supporting cylindrical chambers 7 below its inner face. Each of the chambers 7 connects with a groove 8 which is co-extensive with the chamber 7, both groove and chamber being relatively shorter than the refractory member 6. The side walls of the groove 8 are substantially radial to the center of the cylindrical chamber 7 and are so located as to enclose an angle of substantially 90° therebetween.

75 A helically wound resistor wire 9 is located in the chambers 7 and has its terminals connected to contact terminals 10 which are shown in the drawing as comprising a short screw located in a radially-extending slot 11.

80 A flat bar or strap member 12 is used as a current conducting member between the terminal members 10 of the heating element proper and contact members 13 mounted on a suitable base 14 of insulating material located beneath the heating elements in a 95 manner to be hereinafter set forth. The bar members 12 serve not only to conduct the current to and from the resistor itself but also serve as means for holding two or more of the refractory resistor-supporting 100 members 6 in operative position relative to each other. If it is desired to build up a heating element of relatively small capacity, two of the semi-tubular members 6 only may

105 be employed, while, if it is desired to build up a heating element of greater capacity,

two, or even more of the members 6 may be located one above the other and the length of the bar members 12 may be made such that they will be practically co-extensive with the 5 overall length of the assembled members 6.

In order that the contact terminals 12 and 13 may operate at a relatively low temperature, they are located beneath the heating element proper in a ventilated terminal 10 chamber 14^a. A substantially cylindrical plate 15, having a circular opening 16 there-in, slightly larger in diameter than the diameter of the member 1, forms the bottom plate of the chamber 14. A smaller plate 15 15 17 is spaced apart from the plate 15 by means of a cylindrical member 18, which member is provided with ventilating holes 19, and has provision at one place on its periphery for suitably mounting a control 20 switch 20. The insulating base 14 is secured to the member 17 by means of screw 21.

A suitable insulating bushing 22 is located 25 in the member 15, through which conductors 23 of a supply circuit may be brought and suitably connected to the switch 20. Suitable openings 24 are provided in the member 14 through which the bar members 12 extend when the device is assembled. A 30 substantially circular cover member 25 is provided at the top of the assembled heating device. A body of heat-insulating material 26 is located immediately outside of the assembled semi-tubular members 6 and 35 may be further held in its operative position by means of a cover member 27 comprising bent thin sheet metal, the top and bottom edges of which are held by the flanges 28 on the members 17 and 25.

40 After the desired number of semi-tubular members 6 have been assembled in longitudinally aligned operative position and held in place by means of the bar members 12 and screws 10, the two sets of semi-tubular 45 members 6 may be assembled in place above the terminal chamber 14^a on the base 17 by inserting the lower end of the members 12 into the openings 24 and forcing them into operative engagement with the contact 50 terminals 13 which, as shown in the drawing, may comprise resilient jaws of the usual type used in knife switches. The heat-insulating material 26, pre-formed to substantially semi-tubular shape, may then be applied to the outside of the tubular members 6 after which the sheet cover member 27 55 may be placed in operative position and the cover member 25 placed in position and secured by screws (not shown).

60 Fig. 5 shows the device as assembled and connected by means of pieces of pipe 4 and 29 to the ordinary hot-water tank 5.

It will be noted that our invention provides a relatively simple and easily assembled device in which a relatively large part 65

of the heat is radiated directly against the outer surface of the fluid conducting member 1 and in which any desired number of resistor-supporting members may be combined to form a heating device of the desired heat 70 capacity. Our device also provides novel and effective means for connecting the various units of the device to each other, these means serving also to hold the resistor supporting members in proper operative relation to each other.

While we have illustrated a specific embodiment of the device embodying our invention, various changes may be made therein without departing from the spirit and scope 80 of our invention and we desire that only such limitations shall be placed thereon as are imposed by the prior art or are specifically set forth in the appended claims.

We claim as our invention:

1. In an electrical heating apparatus, the combination with a refractory supporting member of arcuate shape in lateral cross-section, having a plurality of longitudinally extending grooves in one surface thereof, of 90 a helically-wound resistor located in said grooves, and terminal members operatively engaging the ends of said resistor.

2. In an electrical heating apparatus, the combination with a refractory supporting 95 member of substantially semi-tubular shape, having a plurality of longitudinally extending grooves in the inner surface thereof, of a helically-wound resistor wire located in said grooves, and terminal members operatively 100 engaging the ends of said resistor wire.

3. In an electrical water heater, the combination with a plurality of superposed refractory supporting members of substantially semi-tubular shape having a plurality 105 of longitudinally extending grooves in the inner surface thereof, a resistor located in said grooves, and terminal members on the outside of said supporting member connected 110 to the ends of said resistor of current-conducting and supporting-member-alining means electrically connected to said terminal members and extending longitudinally of 115 said supporting members.

4. In an electrical water heater, the combination with a plurality of substantially semi-tubular refractory supporting members each having a plurality of longitudinally-extending grooves in the inner face thereof, of a helically-wound resistor located in said 120 grooves, supply-circuit terminal members, and means for electrically connecting the resistors in the supporting members to each other and to the supply-circuit terminals.

5. In an electrical water heater, the combination with a tubular fluid container, of a plurality of substantially semi-tubular refractory members each having a plurality of longitudinally-extending grooves in its in 125 130

- ner face, a resistor located in the grooves of each of said refractory members, a terminal chamber located below said refractory members, contact terminals located in said 5 chamber, and means for electrically connecting the various resistors to each other and to the contact terminals.
6. In an electrical water heater, the combination with a tubular container, of a plurality of substantially semi-tubular refractory members each having a plurality of longitudinally-extending grooves in its inner surface, an electrical heating means located in said grooves, a terminal box adapted to 10 support said refractory members, contact clips in said terminal box, and means for electrically connecting said heating means to each other and to the contact clips.
7. In an electrical water heater, the combination with a tubular container, of a plurality of substantially semi-tubular refractory-supporting members, each having a plurality of longitudinally-extending grooves in its inner surface, an electrical heating 15 means located in said grooves, a terminal box surrounding said tubular container and adapted to support said refractory members, contact clips in said terminal box, means for electrically connecting said heating means to each other and to the contact clips, and means surrounding said refractory supporting members for holding them in operative 20 position relative to said tubular container and for reducing the amount of heat radiated from the outside of said refractory supporting member.
8. An electrical water heater comprising a terminal box, contact terminals therein, a plurality of longitudinally grooved substantially semi-tubular refractory resistor-supporting members mounted on said terminal box, a resistor mounted in the grooves in said refractory supporting members, and means extending longitudinally of said resistor supporting members for electrically connecting said resistors to said contact terminals by placing said supporting members in proper operative position on said terminal box.
- 50 9. An electrical water heater comprising a terminal box, contact terminals therein, a plurality of substantially semi-tubular cooperating refractory resistor-supporting members mounted on said terminal box, a resistor mounted in the inside face of said 55
- resistor-supporting members, means for electrically connecting said resistors and said contact terminals, and circuit-controlling means mounted on said terminal box.
10. In an electrical water heater, the combination with a ventilated terminal box and contact terminals therein of a plurality of substantially semi-tubular refractory supporting members supported by said terminal box, a resistor located in each of said supporting members, and means for electrically connecting said resistors to each other and to the contact terminals and for maintaining said refractory supporting members in their operative position.
11. An electrical water heater comprising a supporting member, contact terminals mounted thereon, a plurality of heating elements located on said supporting member, contact terminals on said heating elements adapted to operatively engage the contact terminals on said supporting member, said heating elements and terminals being adapted to be quickly removed as a unit, from said supporting member, a heat insulating jacket surrounding said heating elements and means for holding said jacket in its operative position.
12. In an electrical water heater, in combination, a terminal box, a plurality of contact terminals therein, a plurality of superposed electric heating units located above and supported by said terminal box, and means for electrically connecting said heating units to each other, for maintaining them in operative position relatively to each other, and for electrically connecting them to said contact terminals.
13. In an electrical water heater, in combination, a terminal box, a plurality of contact terminals therein, a plurality of superposed electric heating units located above and supported by said terminal box, and means for electrically connecting said heating units to each other, for maintaining them in operative position relatively to each other, and for electrically connecting the said heating units to said contact terminals by placing them in proper operative position on said terminal box.

In testimony whereof, we have hereunto subscribed our names this 6th day of July, 1920.

FRANK THORNTON, JR.
FRANK E. FORSHEE.
